AIR DISTRIBUTING APPARATUS FOR
VENTILATING SYSTEMSAlfred S. Chipley, Chicago, Ill., assignor to Bur-
gess Battery Company, Chicago, Ill., a corpo-
ration of Delaware

Application June 30, 1941, Serial No. 400,486

3 Claims. (Cl. 98—14)

This invention concerns the distribution of ventilating air into enclosures. The specification herein forms part of a divisional application, the invention being described in the co-pending application of Alfred S. Chipley, Serial No. 245,807, filed December 15, 1938, now Patent 2,251,660, granted August 5, 1941.

The manner of introduction of the air into an enclosure to be ventilated has an important bearing on the suitability of every ventilating system. A number of factors must be considered and much ingenuity has heretofore been applied in the solution of the many problems involved in this operation. The difficulties to be overcome have been greatly multiplied by the advent of air conditioning whereby the ventilating air is cooled, when required, to maintain the desired conditions within the enclosure. An ideal air-distributing arrangement is one which delivers conditioned ventilating air into the enclosure in sufficient quantities without concomitant formation of sensible drafts and which will maintain uniformity within the enclosure with respect to temperature and humidity conditions and wholesomeness of the air.

Divers forms of apparatus have been developed and commercially adopted which are capable of satisfactorily distributing ventilating air into an enclosure. The most desirable forms, however, are expensive and occupy space which would otherwise be available for use by the persons or materials within the enclosure.

It is an object of this invention to provide air-distributing apparatus which will distribute a predetermined quantity of ventilating air into an enclosure without drafts and which will operate to so distribute the air that uniform conditions of temperature, humidity and wholesomeness will obtain within the space. Further objects include the provision of such apparatus which occupies a minimum of space and is in a simple and inexpensive form.

In carrying out the invention, a panel of perforated sheet metal or other thin self-sustaining material is used in association with a closed distributing duct of relatively small cross-sectional area. Ventilating air is continuously supplied to the distributing duct and means are provided for turning the rapidly flowing stream of air to cause it to pass through the perforations of the panel into the enclosure to be ventilated in a direction substantially perpendicular to the plane of the panel. An ordination of narrow baffle surfaces, provided by unrolled expanded sheet material arranged adjacent the perforated panel, comprises the turning means. A second perforated

panel controls the rate of flow of air from the duct to the baffle turning means. The invention is fully described hereinafter in conjunction with the accompanying drawing, in which,

5 Fig. 1 is a perspective view, partly in section, showing an air-distributing panel embodying the invention installed in a vehicle;

Fig. 2 is a fragmentary plan view of the panel showing its details of construction;

10 Fig. 3 is a detailed sectional view taken at line 3—3 of Fig. 2; and

Fig. 4 is a detailed sectional view taken at the line 4—4 of Fig. 3.

15 Pay space is at a premium in vehicles and vessels so that ventilating equipment occupying a substantial portion of such space is not desirable. At the same time, the height of motor cars and buses and railway cars is limited by various factors. Buses and railway cars generally have been 20 ventilated simply by blowing air into one end of the enclosure, no attempts having been made to effectively distribute the air to obtain uniform temperature and wholesomeness conditions within the enclosure.

25 An effective air-distributing arrangement which occupies a minimum of space is illustrated in the drawing. Outer shell 1 and inner shell 2 form the body of the motor bus shown in Fig. 1. A closed plenum chamber or distributing duct 3 is 30 formed subjacent roof 4 of the bus. Channel members 5 and 6, which may be integral with inner shell 2, form the side walls of the distributing duct and air-distributing panel 7 forms the floor of the duct. Ventilating air, which may be conditioned as desired, is continuously supplied to distributing duct 3 at either the front or the rear end of the bus body by means of a suitable blower indicated diagrammatically at 11 and supply duct 12. This air passes into the body enclosure 40 through distributing element 7.

35 The details of air-distributing unit 7 are shown in Figs. 2—4. The body of this unit comprises a perforated sheet panel 8 (preferably of sheet metal although other self-sustaining sheet material may be used with slight modifications in the details of construction), this panel having retroverted marginal portions adapted to receive the ends of perforated panel 9 to hold the latter in position. A layer of unrolled expanded sheet material 10 is sandwiched between the perforated panels 8 and 9. As is indicated in the detail figures of the drawing, this expanded sheet material, which may be expanded paper, for example, is made up of a large number of narrow baffles or 50 webs which are angularly disposed to the plane

of the layer and thus of the perforated panels 8 and 9. If expanded paper or other only semi-rigid sheet material is used, it is preferably varnished or otherwise treated after the expanding process to set the structure.

Ventilating air is conveniently introduced into distributing duct 3 at the forward end of the body of the bus by means of a suitable blower 11, shown diagrammatically in Fig. 1, and supply duct 12. Due to the relatively small cross section of this distributing duct, the air within the duct flows rearwardly at a relatively high velocity. It is necessary to turn this air stream approximately ninety degrees in introducing the air into the enclosure and directing it to all parts thereof. At the same time, it is desirable that approximately equal portions of the ventilating air enter the enclosure at all parts of distributing unit 7. Both of these results are accomplished by the combination of the invention. The panel 9 is perforated only to such an extent in relation to the volumes of air supplied to the distributing duct that an appreciable static pressure is maintained within the duct. This condition results in a positive flow of air through the distributing panel throughout its area. Frictional resistance to flow within the duct also contributes to uniformity of flow through the distributing panels since the effect of such resistance is to counteract the tendency of the air, due to its inertia, to flow through the duct to the rear of the vehicle.

The air in passing through the perforations of a single thin panel, such as panel 9, would tend to drift along the under surface of this panel in the same direction as the direction of flow of the air within distributing duct 3. The expanded material is so oriented in the assembly that its structure, including particularly the multiplicity of small baffle members, is disposed predominantly transversely of the air stream within the duct. The purpose of the expanded sheet material is to change the direction of flow of the air which has passed through the perforations in panel 9 and direct it downwardly through the perforations in panel 8 and into the enclosure. Each one of the multiplicity of angularly disposed baffles of the expanded sheet material operates to turn downwardly a small part of the air flowing through the panel 9. The relationship

between the baffle surfaces and the panels 8 and 9 is indicated in Figs. 3 and 4. With full expansion of the expanded sheet material, the baffles may be brought to a position almost perpendicular to the general plane of the material and the ventilating air introduced into the space to be ventilated at substantially right angles to the distributing unit.

I claim:

- 10 1. In a ventilating system including a distributing duct having at least one side exposed to an enclosure to be ventilated and being otherwise closed and means for continuously supplying ventilating air to said duct, a perforated panel forming a wall of said duct in an exposed side thereof, a layer of unrolled expanded sheet material interiorly contiguous said panel with respect to said duct, the orientation of said expanded sheet material being such that the structure thereof is disposed predominantly transversely of the air stream within said duct, and a second perforated panel substantially coextensive with said first mentioned perforated panel and contiguous to said expanded sheet material and disposed on the side thereof opposite said first-mentioned perforated panel.
- 15 2. In air-distributing apparatus comprising a pair of spaced, substantially parallel and coextensive perforated panels forming the exposed wall of an otherwise closed ventilating air distributing duct, a layer of unrolled expanded sheet material arranged between said panels with the structure thereof oriented predominantly transversely of the air stream within the duct.
- 20 3. In a ventilating system including a distributing duct having at least one side exposed to an enclosure to be ventilated and being otherwise closed and means for continuously supplying ventilating air to said duct, a pair of spaced, substantially parallel and coextensive perforated panels forming a wall of said duct in an exposed side thereof, the total open area of the perforations in the inner panel of said pair being so correlated with the volumes of air being supplied to the duct that an appreciable pressure is maintained therein, and a layer of unrolled expanded sheet material disposed between said panels and substantially coextensive therewith.
